UNITED STATES PATENT OFFICE.

ALVIN L. FISHER, OF NEW BRUNSWICK, NEW JERSEY, ASSIGNOR TO THE
CONSOLIDATED FRUIT JAR COMPANY, OF NEW YORK, N. Y.

DESIGN FOR AN OILER.

SPECIFICATION forming part of Design No. 21,671, dated June 28, 1892.

Application filed May 26, 1892. Serial No. 434,481. Term of patent 14 years.

To all whom it may concern:

Be it known that I, ALVIN L. FISHER, a citizen of the United States, residing at New Brunswick, in the county of Middlesex and State of New Jersey, have invented and produced a new and original Design for Oilers, of which the following is a specification, reference being had to the accompanying drawings, forming part thereof.

10 This design has for its object to provide a novel and pleasing oiler, and the leading features thereof reside in an oiler having flat faces and flat sides and having its faces provided with rounded or circular plates or panels.

15 The design is illustrated by the accompanying drawings, in which—

Figure 1 shows a face elevation of the oiler. Fig. 2 is a section along $x x$, Fig. 1.

In the drawings the letters A A indicate the flat faces of the oiler, and B B are the flat sides. The faces A are each provided with a circular or round plate or piece C, surrounded by a rim or bead D. The bottom or lower part E is shown somewhat contracted to form a rim or shoulder F.

20 What I claim as new, and desire to secure by Letters Patent, is—

25 The design for an oiler, substantially as shown and described.

30 In testimony whereof I have hereunto set my hand in the presence of two subscribing witnesses.

ALVIN L. FISHER.
